OIL DISTRIBUTING APPARATUS

Filed March 5, 1945

UNITED STATES PATENT OFFICE

2,467,722

OIL DISTRIBUTING APPARATUS

David B. Baker, Riverside, Ill., assignor to International Harvester Company, a corporation of New Jersey

Application March 5, 1945, Serial No. 581,111

6 Claims. (Cl. 184—6)

1

This invention concerns systems for distributing oil in desired small quantities to several points and relates more in particular to a type of apparatus in which the oil is discharged past weir means into passages leading to the respective points.

Oil distributing apparatus constructed according to the invention is especially useful in the picking units of cotton harvesting machines of the general character disclosed in U. S. Patent No. 2,140,631 to E. A. Johnston. Such units embody a picking spindle carrier rotatable about a vertical axis and having a great number of spindle bearings and spindle driving gears all spaced radially from the carrier axis. These gears and bearings require a lubricant in ample amount because of their rapid and continuous operation, and although the quantity of lubricant (which thus far has been oil) required at the various points is small, it should not exceed the required amount to thereby insure the deposit of none on the cotton crop. Cotton splotched with oil is lowered in grade.

A general object of this invention is the provision of an oil distributing system employing a device adapted to distribute small quantities of oil in equal or other predetermined relative amounts and not materially affected in its accuracy by slight tilting, tossing or vibrations to which it may be subjected while in use upon a vehicle such as a cotton picking machine.

A more specific object is the provision of an oil distributing device rotatable about an upright axis coaxial with an oil containing pocket therein, together with a plurality of distributing channels and weir means over which the oil flows from the pocket into the channels.

A further object is the provision of a device as in the next preceding object but having a plurality of weirs respectively communicating with the passages or channels to direct the oil thereinto from the pocket upon the oil level attaining a certain height therein.

A still further object is the provision of a flow regulating member disposed in the pocket in opposed contiguity with the weir means to resist irregularities occurring in the oil level and thereby contribute to the evenness of the oil feed rate into the channels.

These and other desirable objects will be more readily apparent after reading the ensuing description with reference to the drawings, wherein:

Fig. 1 is a fragmentary sectional view taken upon a vertical plane extending diametrically

2

through the rotatable structure of a cotton picking unit embodying a form of the invention; and

Fig. 2 is a fragmentary sectional view taken horizontally upon the line 2—2 of Fig. 1.

The oil distributing device is generally designated 10 and is mounted coaxially with a rotatable carrier structure 12 of the cotton picking unit. This cotton picking unit is of the general character of that disclosed in the aforesaid Patent No. 2,140,631. Carrier 12 rotates about a vertical axis *a—a* and is driven by a drive shaft 13 welded to an upper end plate 14 of the carrier at 15. This plate 14 cooperates with a bottom plate (not shown) for supporting a plurality of hollow spindle-carrying bars 16 which are arranged vertically and are spaced circumferentially about the carrier. The upper plate 14 is provided with a plurality of bearings 17 respectively for upper end portions of the circumferentially spaced spindle-carrying bars 16, and the lower plate (not shown) is provided with similar bearings for lower end sections of said bars.

Each carrier bar 16 supports a plurality of vertically spaced picker spindles 18 having beveled gears 19 upon ends thereof projecting into the interior of their bars. Gears 19 are driven by companion gears 21 constrained for rotation with an associated shaft 22, there being a shaft 22 in each of the carrier bars 16. The shafts 22 are piloted in ball bearing units 23 spaced axially thereof and carried upon the carrier bars. All of shafts 22 are driven in the same direction by gears 24 upon their upper ends which mutually mesh with a large sun gear 25 which is rotated by a large tubular drive shaft 26 secured thereto by cap screws 27. Concentricity is maintained between the sun gear 25 and the carrier 12 by a ball bearing unit 28. The bars 16, which are oscillatable within their bearings as 17, are controllable in the angularity of their oscillation by arms 29 respectively secured to their upper ends. These arms 29 are oscillated by cam means (not shown) for causing the spindles 18 on their associated bars 16 to enter the crop plants perpendicularly to the rows during that cycle in the rotation of the carrier 12 when the spindles are presented to the crop row and likewise be maintained perpendicular to the row and to be withdrawn perpendicularly therefrom.

Referring now to the oil-distributing apparatus, it comprises a cylindrical receptacle member 31 containing a pocket 32 disposed coaxially of the axis *a—a*. This receptacle is fitted into an inverted cylindrical recess 33 within the lower end of the carrier drive shaft 13 where it is ad-

justably held in an axial direction by machine screws 34. A packing ring 35 within a circumferential groove of the receptacle cooperates with the side walls of the recess 33 in preventing leakage.

In the upper outer end portion of the receptacle 31 there are a plurality of radiating oil-conducting channels 36 which are disposed in respective registry with oil conducting passages or channels 37, each of which comprises a counterpart in the form of a radial hole 38 in the lower end portion of the carrier drive shaft 13, a radial bore 39 in the carrier end plate 14, and a tube 41 projecting from the outer end of its associated bore 39 into a respectively associated one of the hollow spindle-carrying bars 16. Each bar 16 and the shank of its associated control arm 29 is slotted as at 42 for accommodating the tube 41 therefor. The tubes 41 are open at their outer ends 43 for discharging into their associated spindle-carrying bars 16. Oil discharged from the end of each tube 41 falls onto the uppermost gear 21 which centrifugally throws part of this oil onto the inner periphery of its tube 16, whereby the oil descends upon said inner periphery and downwardly of the shaft 22 for lubricating all the gears 21 and 19 and for conduction axially of the spindles 18 for lubricating their bearings 44.

Referring again to the receptacle 31, weir means is provided thereon for conducting the oil from the receptacle pocket 32 into the channels 36 from where it flows into the channels or passages 37 for lubricating the parts within and carried by spindle-carrying bars 16 in the above-described manner. In the present embodiment, this weir means comprises a plurality of weirs 45 respectively registering and communicating with the channels 36 and separated from one another by radially extending upstanding bosses 46.

Oil is fed into the device 10 by a metering device (not shown) mounted upon a portion of the picking unit casing 47. Said metering device is connected with a threaded aperture 48 in the casing and feeds downwardly into the receptacle pocket 32 through a tube 49 which carries a flow-regulating member 51 upon its lower end. The lower end of a bore 52 in the member 51 completes the communication between the tube 49 and the receptacle pocket. Said tube 49 and the member 51 are supported non-rotatably.

In the operation of the device, oil is permitted to drop downwardly through the tube 49 at a slow rate, for example, 15 to 25 drops per minute. This oil accumulates in the receptacle pocket 32 and eventually fills this pocket to its brim or to the weir means 45. Upon the oil rising to the height of the weir means, it will commence to flow thereover into the channels or passages 36 and thence through the passages 37 for lubricating the parts contained in and carried by the spindle carrier bars 16.

While the machine is in operation, the carrier 12 and therefore the receptacle 31 will be rotating about the axis $a-a$ so that the centrifugal force upon the oil in the pocket will tend to overcome inequalities of the oil level within the pocket. Such inequalities may otherwise exist because of tossing and vibrational motion imparted to the device by the vehicular picking unit as it traverses an uneven or unlevel course. Also during operation of the machine as upon a hillside the axis $a-a$ while then generally upright would not be exactly perpendicular. The centrifugal action of the rotating receptacle 31 also tends to overcome gravitational movement of the oil toward one

side of the receptacle pocket during operating positions when the axis $a-a$ is not strictly vertical.

The oil flow regulating member 51 also contributes to the maintenance of the upper surface 5 of the oil in the pocket 32 in uniform relation to the weirs 45. The lower end of the member 51 is normally at a slightly lower elevation than that of the weirs and is therefore in an opposed contiguous relation with respect thereto within the upper portion of the oil body within the pocket 32. This member 51 thus serves to trammel swishing of the oil within the pocket, and since the member 51 is stationary while the side walls of the receptacle revolve thereabout, there is a constant redistribution of the oil circumferentially of the pocket to overcome any tendency for the oil to collect and build its upper surface to a higher elevation at any one section than at other sections. The just-described features of the device cooperate to maintain a uniform oil level, and uniform feeding of the oil over the weirs 45 is supplemented by the internal cohesive properties of the oil itself, so that all these features functioning collectively cause the device to distribute a small quantity of oil with adequate precision even when the machine upon which the device is run is traversing rough and/or unlevel terrain.

While in the present installation it is desirable for the distributing device 10 to cause equal minute quantities of oil to be delivered through the passages 37, it would be possible to incur unequal predetermined relative fixed amounts of oil through said passages. This may be done, for example, by forming some of the weirs 45 lower with respect to the others when it should be desired to increase the relative flow past these relatively lower weirs. Different flow rates through the weirs may also be obtained by forming the device with relatively wider weirs (circumferentially of the receptacle) at the points where greater flow is desired.

Having thus described the preferred form of my invention with the view of fully illustrating the same,

I claim:

1. In an oil distributing device, a structure rotatable about a vertical axis, said structure having an oil receiving pocket coaxial with said axis and a plurality of outlets through which the oil received by said pocket is to be discharged in equal quantities, said structure comprising weir means spaced radially from such axis and over which the oil spills from the pocket, and said weir means being disposed above said outlets and for directing the spilled oil thereinto.

2. In an oil distributing device, a member rotatable about a vertical axis and having an inverted cavity coaxial with such axis, a plug-like structure insertable into said cavity to close the same and to rotate with said member, said structure having an oil receiving pocket also coaxial with said axis, said structure having a brim about said pocket and a plurality of outlets through which oil received thereby from said pocket is to be discharged in equal quantities, said outlets being communicative with the pocket over the brim thereof and being below such brim, and means projecting upwardly from said brim to segregate sections of the latter for the flow thereover of oil from the pocket into respective of said passages.

3. In an oil distributing device, a receptacle rotatable about an upright axis coaxial with an oil receiving pocket therein, said receptacle having oil outlet passages, a plurality of weirs ro-

tatable with said receptacle and spaced circumferentially about the side walls of said pocket at an elevated position with respect to the bottoms of said passages, said weirs respectively communicating with said passages and being adapted for the flow of oil therewith into the passages upon the oil reaching sufficient height in said pocket.

4. In an oil distributing device, a receptacle rotatable about an upright axis coaxial with an oil receiving pocket therein, said receptacle having oil outlet passages spaced circumferentially about its side walls, weir means above the bottoms of said passages and over which the oil can spill from the receptacle into said passages when the upper surface of the oil reaches an adequate height in the receptacle, and an oil flow regulating member depending into the pocket in opposed contiguity with said weir means and to a sufficient depth for at least partial immersion by the oil to dampen localized variations in the height of such upper oil surface.

5. The combination set forth in claim 5, and wherein said regulating member has an inlet passage for directing oil axially and centrally into the receptacle pocket.

6. In an oil distributing device, a receptacle

having an oil receiving pocket disposed with its principal axis upright, said receptacle having oil outlet passages, a plurality of weirs on said receptacle above the bottoms of said passages and spaced circumferentially about the side walls of said pocket, said weirs respectively communicating with said passages and being adapted for the flow of oil therewith into the passages incident to the surface of the oil reaching sufficient height in the pocket, an oil flow regulating member disposed in the receptacle pocket coaxially therewith and in opposed contiguity with said weir means to dampen localized variations in the height of such upper oil surface, and mounting means for said member and said receptacle for accommodating their relative rotation about said axis.
